CLAIM

The ornamental design for a dripless medicine dropper, as shown and described.

DESCRIPTION

FIG. 1 is a front elevational view of a dripless medicine dropper of the present invention;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a front elevational view thereof, in exploded position, it being understood that all undisclosed sides of the two central elements are the same as shown on the front side of said elements.
